(57) **CLAIM**

The ornamental design for an aerosol-generating capsule, as shown and described.

DESCRIPTION

FIG. 1 is a first top perspective view of an aerosol-generating capsule showing our new design.

FIG. 2 is a second top perspective view of the aerosol-generating capsule of FIG. 1.

FIG. 3 is a first bottom perspective view of the aerosol-generating capsule of FIG. 1.

FIG. 4 is a second bottom perspective view of the aerosol-generating capsule of FIG. 1.

FIG. 5 is a top plan view of the aerosol-generating capsule of FIG. 1.

FIG. 6 is a bottom plan view of the aerosol-generating capsule of FIG. 1.

FIG. 7 is a first side view of the aerosol-generating capsule of FIG. 1.

FIG. 8 is a second side view of the aerosol-generating capsule of FIG. 1.

FIG. 9 is a proximal end view of the aerosol-generating capsule of FIG. 1; and,

FIG. 10 is a distal end view of the aerosol-generating capsule of FIG. 1.

The broken lines in the drawings depict portions of the aerosol-generating capsule that form no part of the claimed design.
